UNITED STATES PATENT OFFICE.

WILLIAM G. ALLAN, OF TORONTO, ONTARIO, CANADA, ASSIGNOR, BY MESNE ASSIGNMENTS, TO FARLEY G. CLARK.

ELECTROLYTIC APPARATUS.

Application filed November 10, 1923, Serial No. 674,048. Renewed May 23, 1927.

The invention relates to apparatus adapted for electrolytic production of materials or substances in the solid, liquid or gaseous state, and while the apparatus illustrated and described herein is intended for the purposes of electrolytic decomposition of an electrolyte into its gaseous constituents, or into such parts of its constituents as will appear at the electrodes in gaseous form, as for example, an aqueous solution of an acid or an alkali whence may be produced oxygen and hydrogen gases, the invention is not limited to such use, but may be employed in the art of electrolysis generally.

The objects of the invention are to improve and cheapen the construction, and to increase the efficiency of apparatus of the character described; to provide an apparatus which is compact; which is of rugged construction; which will not easily get out of order; which will be easy of repair; which will be flexible; which will occupy a relatively small superficial and cubical space; and wherein the rate of gas production, and in consequence the forces and quantities of energy to be dealt with, are very great.

A further object is to provide means for separating out the three phases of matter, solid, liquid and gaseous, of the electrolyte, and to provide means for the withdrawal of one or more of said phases, and for the return of one or more of them to the apparatus.

A further object is to provide means for regulating, controlling, and increasing the purity of the electrolytic products, and for regulating, controlling, and in some cases equalizing, or tending to equalize, the densities of the electrolytic solution which may tend to become different in different parts of the apparatus.

A further object is to provide means for relieving the apparatus of accumulations of electrolytic or other products which may tend to collect in the apparatus.

A further object is to insert at various points in the apparatus, insulating means whereby efficient operation and purer products will be assured, and which will guide the flow of current through the apparatus, and which will prevent, or limit stray currents.

These and further objects will more fully

appear in the following specification and accompanying drawings considered together or separately.

Reference is here made to U. S. Letters Patent Nos. 1,464,840 and 1,592,512 issued to me under the dates of August 14th, 1923, and July 13th, 1926, respectively.

The drawings illustrate one embodiment of the invention, in which like parts in all the several figures are designated by corresponding characters of reference and in which

Fig. 16 is an end elevation of a pipe insulation section, and

Fig. 17 is a longitudinal section on the line 19—19 of Fig. 16.

In the embodiment of the invention illustrated, the apparatus comprises a plurality of cell groups A arranged in electrical series. Each group preferably comprises a plurality of cell units B. The number of units in a group, and the number of groups in the apparatus may be varied as desired. In the drawings each unit comprises a cell wall or partition 1 of

thin sheet steel, for example, clamped between the inner flanges 2 of two frame members 3. The members 3 are each provided with an outer flange 4 as shown. Each wall, except those forming the end walls of the group of units, carries on each side thereof an electrode of any suitable form. Each end wall of the group carries one electrode. When the units are assembled a porous diaphragm 5 is clamped between the flanges 4 of adjacent units. The diaphragms 5 and partitions 1 alternate throughout the group, and an electrode is positioned parallel to and in close proximity to each face of each diaphragm whereby when the cell spaces between the partitions are filled with a suitable electrolyte, and an electric current is passed through the group, oxygen will be formed at the anode and hydrogen will be formed at the cathode. The anolyte cell space of one unit is separated from the catholyte cell space of the adjoining unit by a diaphragm 5 through which the electrolyte may pass, but which will prevent the passage of the gas.

Figs. 1, 3 and 4 of the drawings illustrate two groups of units, but it is to be understood that any desired number of units connected in series may be employed. The drawings show six units in each group, but this number is merely illustrative, and is selected for the reason that a group of such size may be easily handled.

Each anolyte frame member 3 is provided with two openings 6 and 7 and each catholyte frame member 3 is provided with two openings 8 and 9. A return flow manifold 10 is in communication with the openings 6 of each group. A similar manifold 11 is in communication with the openings 9 of each cell space of each group. A manifold 12 is in communication with all of the openings 7 and a manifold 13 communicates with the interior of the cells through the openings 8 of each group. The openings 8, and the manifold 13 are of greater capacity than the openings 7 and manifold 12.

A tubular riser 14 leads from each manifold 12 and connects with an oxygen-anolyte header 15, and a tubular riser 16 leads from each manifold 13 to a hydrogen-catholyte header 17. The headers 15 and 17 are positioned some distance above the tops of the cells as shown in Fig. 1. The header 15 connects with the upper part of an oxygen separating tank 18, and the header 17 enters the upper part of a hydrogen separating tank 19.

The manifold 10 communicates with a header 20 which is in communication with the lower part of the tank 18, and the manifold 11 is connected to a header 21 which enters the lower portion of the tank 19. These main headers 15, 17, 20 and 21 serve the combined purpose of conveying the

gaseous products of electrolysis along with entrained electrolyte from the electrolytic cells to the separating tanks 18 and 19 wherein separation of gaseous products from the liquid electrolyte is effected, and for providing for the return flow of electrolyte, substantially free of gas, from the tanks to the cells whereby a closed circuit for the electrolyte will be maintained.

As shown in the drawings the manifolds 10 and 11 communicate with the bottoms of the cell spaces whereby the gas-free electrolyte will not move contrary to the path of the ascending gases.

The discharge from the headers 15 and 17 into the tanks 18, and 19 respectively is through insulating pipe sections 22 and 23. The mixture of gas and electrolyte carried by the automatic gas-lift action over into the tanks, will be discharged above the level of the electrolyte in the tanks.

Suspended within each tank 18 and 19 is a screen 24. The screen may be a single sheet or any desired number of sheets, of perforated material, and is supported in an annular frame which latter is hung by wires 124 from a point or points close to the top of the tank. Each wire is provided with a loop which engages over a projection on the inside of the tank, and with a handle 125, whereby the screen may be taken out of the tank for cleaning, renewal or any other purpose when the tank cover has been removed.

The object of the screens, which are preferably composed of a cloth woven of metal which will resist the action of the hot electrolyte and the nascent gases, is to cause the minute gas bubbles suspended in the electrolyte in a state of supersaturated tension, to coalesce to form larger bubbles which burst and allow the gas therein to mingle with the remainder of the gas and rise into the upper part of the tank, and the heavier electrolyte, and such impurities as may be present in the electrolyte, will fall to the bottom of the tank. As the electrolyte proceeds downward in the tank it will lose such fine bubbles of gas which have passed through the screen, and which will coalesce and rise to the surface.

Towards the lower end of the tank 18, but above the bottom thereof, there is a valved outflow connection 25, and a similar connection 26 leads from the tank 19. The connection 25 offers communication with a rediffusion tank 27, and, by means of a valved branch 28 with the return header 20. The connection 26 is similarly connected with the tank 27 and the return header 21 through a valved branch 29. An additional valved connection 30 between the tank 27 and header 20 is provided, and there is a similar valved connection 31 between said tank and the header 21. If desired the electrolyte after being relieved of

its gas may be heated by means of a steam coil 32 in the tank 27, but it is to be understood that any other form of heating device in the tank or at any point or points between the separating tanks and the cells may be employed.

The tank 27 is provided with a thermometer 33 whereby the temperature of the electrolyte may be ascertained, and similar thermometers 34 may be placed in the anolyte and catholyte headers 15 and 17 between the insulating joints 22 and 23 and the tanks 18 and 19.

Observation glasses 35, to be presently specifically described, may be placed at various points in the piping system, and gauge glasses 36 on the tanks 18 and 19 and elsewhere in the apparatus will enable the operator to observe conditions in the system.

In order to promote circulation of the electrolyte and nascent gases through the system it is desirable that at some point in the circulation system, the temperature of the gases, and entrained anolyte and catholyte be lower than that of the electrolyte and gases in the cells whereby the volume of the contents of the system will be reduced either by the contraction thereof due to the lowered temperature, or to condensing effect.

In the embodiment of the invention illustrated, the reduction in temperature is effected in the separating tanks 18 and 19, but it is to be understood that the cooling chambers may be placed elsewhere between the cells and the said tanks.

Preferably the upper portions of the tanks, in which the entrained electrolyte is separated from the gas by gravity, is maintained at a temperature lower than that of the body of electrolyte in the lower portions of the tanks.

This may be accomplished by applying insulating lagging to all of the circulating system, except possibly the cells proper, and leaving the upper parts of the tanks 18 and 19 bare, whereby the room temperature will condense the moisture and entrained impurities, such as NaOH or KOH and cause it to fall into the electrolyte in the lower portions of the tanks before the gases pass out by way of the pipe connections 64. In Fig. 5 the insulation 37 of the lower portions of the tanks is shown in dotted lines.

If desired, the upper portions of the tanks, in which the gas separated from the electrolyte, may be cooled by means of a water jacket 38, as shown in Fig. 6, or by means of a coil through which cooling liquid may circulate.

The bottom of each tank 18 and 19 is preferably of conical form as shown, and each is provided with a valve 118 whereby any solid or semisolid matter may be withdrawn from the tanks, and each of said tanks is provided with a valved drain and

sampling connection 119 whereby samples of electrolyte may be withdrawn for testing.

The feature of providing means for settling, and the removal of solid matter, such as sludge, is of importance for the reason that it is often impossible to secure commercial solvents for the caustic soda or caustic potash which are free from insoluble matter such as silica, alumina, ferric hydrate, lime, magnesia, etc., and if such substances in finely divided state are present, they will be carried over into the separating tanks, and will settle and be deposited in the conical bottoms thereof and be drained off at intervals.

Likewise any solid matter formed in the cells or piping, or any solid matter in the feed water will be thrown over into the bottoms of the tanks, and be removed before it threatens to collect to excess. Because of the settling chamber at the bottoms of the tanks, it will be possible, in many instances, to use undistilled feed water and commercial solvents for the electrolyte without danger of clogging up the system.

Each of the headers 15, 17, 20 and 21 is subdivided into a number of flanged pipe sections, each of which is electrically insulated from each other section, by means of an insulating gasket 39. The flanges of the tube sections are secured together and to the gasket 39 by means of bolts insulated from the flanges by insulating bushings 40. The gasket 39 is preferably of a material which will withstand the action of the hot electrolyte and the nascent gases, and which will have a slight degree of compressibility under the bolt pressure. Compressed asbestos sheet packing is a suitable material for the purpose.

By subdividing the headers in the manner above described, and electrically insulating the several sections from one another, shunt currents are prevented, and the generation of impure gases is reduced to negligible quantity. The number of subdivisions between any two groups of cells in the embodiment of the invention illustrated, is two but the number may be increased, if desired, to secure better results.

Each return manifold 10 is in communication with all of the anode cell spaces of a cell group, and with the return header 20 by means of a valved pipe 41 having an observation tube therein. The manifold 10 is also connected by means of a riser 42 to a relief header 43, composed of insulated pipe sections, to a relief chamber 44 situated at that end of the structure opposite the separating tanks 18 and 19.

Each return manifold 11 is similarly connected through a header 45, to a relief chamber 46 at the same end of the apparatus as the chamber 44. The headers 43 and 45 and the tanks 44 and 46 are placed at a point

higher than any to which the level of electrolyte can rise in the course of operation of the apparatus, and the tanks 44 and 46 are connected to the return headers 20 and 21 respectively by means of risers 47 and 48 each having a valve 49 therein, and each provided with a drain valve 50.

It will be seen that the return flow headers 20 and 21 from the separating tanks 18 and 19 to the cells, and the cell offtake headers 15 and 17 are on a higher level than the tops of the cell casing, and that the relief headers 43 and 45 and relief tanks 44 and 46 are at a higher level than the headers 15 and 17. 15 Any gas which may form in, or find its way into, the electrolyte in the separating tanks or in the return flow connections, will be swept along by the flow of the electrolyte from the chambers and find egress to 20 the relief chambers, and the electrolyte entering the cells will be free of gas. The relief chambers are, in the embodiment of the invention illustrated, open to the atmosphere, but the gases from said chambers may be 25 conveyed to a storage reservoir if desired.

The return flow manifolds 10 and 11 and the offtake manifolds 12 and 13 are connected to their respective cell spaces by means of insulating risers 51 each preferably 30 provided with an observation glass 35.

The construction and arrangement of the manifolds 10 and 11 is as follows:—

The manifold, and its pipe 41 form a U-shape structure with the legs thereof horizontally disposed, with the pipe 41 lying directly below the return header to which it is connected. The free end of the pipe 41 is connected to the underside of the header, and a valve 52 is in the connection. Each 35 manifold is provided with a plurality of depending nipples 53 each of which is connected to a riser 51.

The risers 51 and the insulated pipe sections carrying the observation glasses 35 40 are preferably constructed as follows:—

A heavy walled glass tube 54 is placed in axial alinement between two pipe nipples 55 each threaded at its outer end. Covering each joint between the tube 54 and the nipples 50 is a flexible or semiflexible sleeve 56 of rubber or other suitable material each secured to the tube and a nipple by means of suitable hose bands 57. Secured to the threaded end of each nipple 55 is a union 55 58 by means of which the observation glasses may be secured in a pipe line.

The subdivided headers 15, 17, 20, 21, 43 and 44 are supported by and insulated from a frame consisting of a series of pipe columns 59 arranged in the longitudinal center 60 of the apparatus. Each header rests upon a block 60 of insulating material carried at or near the end of a cross arm 61 clamped to the columns, and the relief chambers 44 65 and 46 rest upon insulating blocks on the

cross arm 61 which supports the headers 15 and 17 at one end of the apparatus.

By clamping the cross arms 61 to the columns, the cross arms may be readily raised or lowered to adjust the levels of the various 70 pairs of headers relatively to the cells and to each other, to facilitate assembly and installation of the apparatus as a whole, and also to permit of adjustment of the amount of the gas lift effect, and of other conditions 75 of circulation and flow of the electrolyte and gases in the system, whereby various pressures, hydrostatic and others, may be balanced on one or both sides, anolytic or catholytic, of the circulating and generating systems. All of which is important to produce 80 conditions effective in yielding gases, or other products of reacting of a maximum degree of purity.

In order to place the headers 15, 20 and 43, or any of them, on levels different from 85 headers 17, 21 and 45, the insulating blocks 60 may be higher on one side of the center line of the apparatus than on the other, or there may be a separate cross arm for supporting each header instead of a single cross arm for supporting a pair of headers, 90 as illustrated.

In connection with the apparatus above 95 described the oxygen from the tank 18 may, if desired, be passed to a cooling, bubbling, and washing tank 62, and hydrogen may enter a similar tank 63. The tank 63 may be approximately double the capacity of the tank 62. The washing tanks are identical, 100 except as to size, and a description of one will suffice for both.

Oxygen will leave the tank 18 through a 105 pipe 64, provided with an insulating observation section 35, which enters the top of the tank 62 and terminates at a point a short distance above the bottom thereof. A screen 65, preferably of the same construction as the screens 24 in the tanks 18 and 19, is carried on the lower end of the pipe 64 and forms a foraminous diaphragm in the tank. 110

Water is admitted to the tank 62 by means of a valved pipe 66, and the water in the tank is maintained at approximately a constant 115 level by means of a standpipe 67 in communication with the tank at the bottom thereof. As will be seen the level of the water in the tank will be considerably above the screen 65 whereby gas escaping from the pipe 64 will bubble up through the screen 120 where the bubbles will be broken up, and the gas thoroughly washed before it is led off by means of a connection 68 at the top of the tank. Each of the washing tanks is provided with a gauge glass, and said tanks 125 are connected together by means of a throttle valved communicating pipe 69, having a valved waste outlet 70.

Another and preferred form of cooling, 130 bubbling and washing device is illustrated

in Figs. 10, 11 and 12. In this construction the oxygen and hydrogen tanks 62 and 63 are of practically the same construction as those above described, but instead of employing overflow weirs of fixed height the 5 same may be adjustable, as shown.

Each overflow weir comprises a stand pipe 71 in communication with its tank 62 or 63 and near the bottom thereof. The 10 standpipe is closed at its bottom, and an overflow pipe 72 extends through the bottom and extends upward in the standpipe.

A tube 73 is telescoped into the pipe 72 and is provided with a series of apertures 74 15 as shown. The tube is provided with a stem 75 which extends through the top of the standpipe, and a set screw 76 may be employed to retain the tube in the desired position relatively to the pipe 72.

20 The washing liquid from the tank will enter the stand pipe and rise to the level of the openings 74 and will then escape through the bottom of the pipe. The adjustability of the tube 73 will be utilized to maintain the 25 level of the liquid in the tank at any height desired.

Instead of employing a separate inlet pipe 66 for each tank, as before described, a vertically arranged cylindrical tube 77, prefer- 30 ably located between the tanks 62 and 63, is employed. The said tube is divided by means of a vertical partition 78 into two chambers 79 and 80. The tube is inserted in the pipe connection 69 between the bottoms 35 of the tanks 62 and 63, the chamber 79 being in communication with tank 62 and the chamber 80 communicating with the tanks 63.

40 The top of the tube 77 is open and washing liquid, water for example, is supplied to the chambers 79 and 80, respectively, by means of faucets 81, 82. The bottoms of the chambers are in communication by means of balancing pipe connections 83 having a 45 trottle valve 84 and a drain valve 85. The tube 77 is provided with a gauge glass 86 to indicate the level of the liquid in one or both of the chambers 79 and 80.

The electrodes employed in the apparatus 50 may be of any suitable type, but preferably each electrode 87 is composed of a plurality of foraminous sheets or plates such for example as of woven wire cloth, the metal of which will not be affected by the electrolyte 55 or by the temperature of the same.

In the preferred electrode the foraminous sheets are fused together at their edges to form a solid border, and the said borders are united, as by welding, to studs 88 projecting from the plates 1 which form the partitions of the cell members.

Each diaphragm is composed of an insulating material which is of such a character that the electrolyte may pass freely through 65 it, but which will prevent the passage there-

through of the gases which will result from the decomposition of the electrolyte or any part thereof.

Each diaphragm is composed of a sheet 5 of the material desired, in the present case 70 a sheet of woven asbestos fabric, of a shape corresponding with the shape of the cell space as defined by the walls 3.

The flanges 4 are provided with openings 75 therein, and, when the cells are assembled, these openings are in alinement, and bolts 95 are passed through all of the flanges of each group, the said bolts being insulated from the flanges by means of washers 96, and spacing collars 97 are threaded on the bolts 80 between the flanges of each pair of cell frames 3.

The operation is as follows:

The cells are filled with electrolyte, as for example an aqueous solution of an acid or 85 an alkali, which will, when the electrolyte is quiescent, stand above the tops of the cells in the outlet and return risers. A suitable electric current is passed through all of the 90 cells in the apparatus to produce gases (oxygen and hydrogen) by the decomposition of the electrolyte.

The formation of the gas or gases, and the heat imparted to the electrolyte by the high current density of the electric current, 95 and by the extraneous heating means when employed, will result in an increase in the volume of the combined electrolyte and gases whereby the same will rise above the normal quiescent level in the offtake risers and manifolds 12 and 13 and into the offtake headers 15 and 17 and flow along the same until the anolyte reaches the separating chamber 18, and the catholyte, reaches the separating 100 chamber 19, where the greater part of the gases will be separated from the electrolyte by gravity, and anolyte or catholyte, as the case may be, will accumulate in the lower portions of the chambers 18 and 19 respectively, and the level of the liquid in the 110 separating chambers is maintained below the points of discharge into said chambers whereby the mixtures of gas and electrolyte which are carried by the gas lift action over into the chambers will be discharged 115 above the level of the electrolyte in the chambers.

The screens or filters 24 will cause the finely divided gas bubbles, suspended in the electrolyte in a state of supersaturated 120 tension, to coalesce and form larger bubbles which break and allow the gas therein to mingle with the remainder of the gas, and rise into the upper parts or domes of the chambers.

The electrolyte after passing through the screens will fall downward, and any entrained bubbles of gas which may have passed through the screens may separate 125 from the liquid and pass upward through 130

the screens and come into the gases in the domes.

Any solid matter in suspension in the electrolyte in the chambers will settle and collect in the conical bottoms of the chambers, and be drawn off from time to time through the valves 118.

The process of ejection of electrolyte and gases from the cells and into the separating chamber is continuous as long as the electric current flows, and it is substantially proportional to the gas lift effect of the oxygen and hydrogen on the analytic or catholytic sides respectively of the circulating system, and, by reason of the proportional buoyancy of said gases, is greater for the hydrogen than for the oxygen. The volume of electrolyte carried from the cells to the separating chambers, in a given time, varies with and is approximately proportional to the volume of gas generated in a given time, or in other words, is proportional to the current flowing.

The result of discharging the electrolyte into the separating chambers is to produce a greater hydrostatic head therein than the hydrostatic head within the cells, and, as the electrolyte is free to return to the cells through the insulated pipes 25, 26, tank 27, headers 20, 21 and manifolds 10 and 11, the flow of the electrolyte is automatic, and proportional to the combined effects of the gas lift of the generated gases and the electric current. The increase of hydrostatic head in the separating chambers, and hence the flow is greater on the hydrogen than on the oxygen side of the system. This is of advantage for the reason that the volume of hydrogen liberated at the cathodes is twice that of the oxygen liberated at the anodes.

The electrolyte in passing from the chambers 18 and 19 pass into the rediffusing tank 27, and are heated by means of the steam coil 32. Feed water to compensate for that which has been decomposed in the cells is admitted to the tank 27 through the three-way valve 27^a in the bottom of said tank.

Other and more complicated phenomena occur, such as the balancing of the endosmotic pressures through the diaphragms with the unbalanced hydrostatic pressures on the analytic and catholytic sides respectively, which would continually tend to reestablish a uniformity of level of the electrolyte through the rediffusion tank, were it not for the said endosmotic pressure. The endosmotic pressure may be described as a force set up by and due to the actual forcing of ions through the pores of the diaphragm by the passage of the electric current.

Any gas which may be retained in the electrolyte after the latter has passed from the tanks 18 and 19 will escape through the risers 42 to the headers 43 and 45 and thence to the tanks 44. Any electrolyte entrained

with such gas or gases may be returned to the headers 20 and 25 by means of the pipes 47 and 48.

The gases in the domes of the chambers 18 and 19 may be drawn off in oxygen and hydrogen holders respectively, but when gases of a high degree of purity are required the gases from the domes pass through pipes 64 into the washing and cooling tanks 62 and 63 respectively, in which the gas is washed and cooled.

The gas escaping through the lower open end of the extension of the pipe 64 will bubble upward through the wash water in the tank and will pass upward through the screen 65 being broken up into fine bubbles, globules or particles, and will be washed and cooled by the subdivided contact with the wash water, as well as by the contact with the wetted and cooled wires of the screen. The gas then rises to the upper portion of the tank, whence it may be conducted to any suitable gasholder, compressor or storage tank.

The height to which the wash water will stand in the cooling tanks will depend upon the pressure of the gases above the surface of the water, the height of the overflow weir 67, and atmospheric pressure.

In addition to washing and cooling the gases, the connected tanks 62 and 63 also act to maintain the pressures of the gases equal, or bearing some definite relation to each other.

If the gases withdrawn from the tanks 62 and 63 are to be compressed, the compressors for the oxygen, and hydrogen respectively may not be compressing at the same time, or they may be compressing at rates which do not bear the same ratio to one another as do the rates at which the gases are being generated in the cells, namely; one volume of oxygen to two volumes of hydrogen. Such unequal suction of the compressors will result in unequalization of the pressures of the gases in the tanks 62 and 63.

If the hydrogen compressor is withdrawing gas from the tank 63 at a rate greater than twice that at which oxygen is being withdrawn from the tank 62, the pressure in the hydrogen in the tank 63 may become lower than the pressure in oxygen tank 62, due to the inadequacy of gas supply, or for other reasons. The result of this would be that, with the valve in the connection 69 wide open, water would flow from tank 62 to tank 63, and the hydrostatic head in tank 63 would be higher than the head in tank 62, the flow of hydrogen into the tank 63 would be lessened by the column of water therein, and the flow of oxygen would be increased because of the low head. This unbalancing of the gas pressure would be felt in the electrolytic cells and apparatus with undesirable results. By operating the valve 130

in the balancing connection 69 as a throttle, the hydrostatic heads in the tanks may be maintained at the desired levels.

In accordance with the provisions of the 5 patent statutes, I have described the principle of my invention together with the apparatus which I now consider to represent the embodiment thereof, but it is desired to have it understood that the apparatus shown is 10 merely illustrative and that the invention may be carried out in other ways.

The invention having been described, what is claimed as new and desired to be secured by Letters Patent, is as follows:—

15 1. An electrolytic apparatus, comprising two closed systems containing electrolyte, each system comprising cells, a separating chamber and conduits connecting the cells and chambers, porous diaphragms separating 20 said systems within the cells, means for balancing the endosmotic pressure produced by the flow of current through the electrolyte in the pores of said diaphragms with the difference in hydrostatic pressures produced 25 in the two chambers belonging particularly to said two systems, and a rediffusing tank common to both of said systems.

2. An electrolytic apparatus, comprising two closed systems containing electrolyte, 30 each system comprising cells, a separating chamber and conduits connecting the cells and chambers, porous diaphragms separating said systems within the cells, means for balancing the endosmotic pressure produced by the flow of current through the electrolyte in the pores of said diaphragms with the difference in hydrostatic pressures produced 35 in the two chambers belonging particularly to said two systems, and a rediffusing tank common to both of said systems, said rediffusing tank being provided with return flow 40 conduits connecting the same with and in the path of the electrolyte between the separating chambers and cells.

45 3. An electrolytic apparatus, comprising two closed systems containing electrolyte, each system comprising cells, a separating chamber and offtake conduits connecting the cells and chambers for conveying the generated products to the separating chambers, 50 porous diaphragms separating said systems within the cells, means for balancing the endosmotic pressure produced by the flow of current through the electrolyte in the pores of said diaphragms with the difference in hydrostatic pressures produced in the two 55 chambers belonging particularly to said two systems, a rediffusing tank common to both said systems, return flow conduits connecting the separating chambers, rediffusing tank and cells so as to position the tank in a path of the electrolyte between the chambers and cells, and means for heating the rediffusing tank.

4. The combination in an electrolytic apparatus of an electrolytic cell comprising an anode side and a cathode side, an anolyte separating chamber in communication with the anode side, a catholyte separating chamber in communication with the cathode side, 70 conduit means for returning electrolyte from said chambers to the cells, oxygen being separated from the anolyte in the upper portion of one chamber and hydrogen being separated from the catholyte in the upper 75 portion of the other chamber, means between the chambers and the cells for admitting feed water to compensate for the decomposition, and means for establishing and maintaining a difference of hydrostatic head of 80 electrolyte between the said chambers and said cells whereby a circulatory flow of electrolyte will be maintained.

5. An electrolyte apparatus comprising a plurality of groups of electrolytic cells arranged in alinement, a series of vertical columns arranged in the longitudinal center of the apparatus, adjustable cross arms carried at different heights on the columns, the anode side of each cell in each group being 85 provided with the tubular riser, all of said risers communicating with an anolyte header, the cathode side of each cell of each group being also provided with a tubular riser, all of the last mentioned risers communicating with the catholyte header, an anolyte separating chamber, a catholytic separating chamber, said headers communicating respectively with the anolyte and catholyte chambers, each of said headers 90 being supported upon and insulated from a cross arm, a tank for receiving electrolyte from said chambers, headers for conveying electrolyte from said tank to each cell unit, 95 said headers being supported upon and insulated from cross bars carried on the columns, gas headers carried on and insulated from the columns, and auxiliary headers offering communication between the electrolyte return headers and the said gas 100 headers.

6. An electrolytic apparatus comprising two closed systems containing electrolyte, each system comprising cells, a separating chamber and offtake conduits connecting the cells and chambers for conveying the generated products to the separating chambers, porous diaphragms separating said systems within the cells, means for adjusting 115 the hydrostatic heads in both systems to balance the endosmotic pressure within the cell produced by the flow of current through the electrolyte in the pores of said diaphragm, a rediffusing tank for the returning electrolyte, and return flow conduits connecting the tank, separating chambers and cells for returning the separated electrolyte 120 to the cells.

7. In an electrolytic cell, the combination with anode and cathode compartments, and a porous diaphragm therebetween, of anolyte and catholyte separating chambers associated therewith, conduit means joining the compartments and chambers respectively, and means for adjusting the heights of the conduits above the level of the electrolyte in the cell compartments to thereby regulate the total pressures in the anode and cathode compartments.
